UNITED STATES PATENT OFFICE.

JOHN LEICK, OF VERONA, NEW JERSEY.

HAIR-FASTENER.

SPECIFICATION forming part of Letters Patent No. 691,555, dated January 21, 1902.

Application filed February 14, 1900. Serial No. 5,185. (No model.)

To all whom it may concern:

Be it known that I, JOHN LEICK, a citizen of the United States, residing at Verona, in the county of Essex and State of New Jersey, 5 have invented a new and useful Hair-Pin, of which the following is a specification.

This invention relates to hair-pins.

The object is to present a hair-pin which will be thoroughly effective for securely holding the hair of the user and which by its construction will be more positively retained in the hair than with devices of the above character in common use.

With these and other objects in view, as 15 will appear as the nature of the invention is better understood, the same consists in the novel construction and combination of parts of a hair-pin, as will be hereinafter fully described and claimed.

20 In the accompanying drawing, forming a part of this specification, and in which like numerals of reference indicate corresponding parts, the figure is a view in elevation of a hair-pin characterizing this invention.

25 The hair-pin of this invention may be constructed of any material suited to the purpose and in one piece, and comprises an elliptical head 1, constituting a hair-confining loop, two legs 2, arranged substantially in parallel 30 relation with each other, each having intermediate of its ends an inward-extending bend or offset 3, lying in a plane parallel with that of the hair-confining loop and constituting combined stops and hair-clamps, and two 35 shoulders or abutments 4, forming a continuation of the legs and merging into the head and operating to limit the inward insertion of the pin.

In the use of the pin the legs are thrust into 40 the hair and a portion thereof will be forced into the hair-confining loop, the bulk, how-

ever, being crowded in between the abutments 4 and the clamps and stops 3, the terminals of the legs serving to hold the pin firmly in position. In the act of inserting the 45 pin the legs will naturally be forced apart, thereby permitting the hair to pass the clamps or stops 3, and as soon as inward pressure is removed from the pin when finally positioned the said clamps or stops will be projected in- 50 ward by the movement of the legs, thereby operating at once to clamp the hair in the space between the shoulders 4 and the clamps or stops and also to bear upon the hair disposed between the clamps. 55

It will be seen from this description that while the device of the present invention is exceedingly simple in construction it will be thoroughly effective in use and will be found to fill a long-felt want in toilet articles for 60 ladies' use.

Having thus fully described my invention, what I claim as new, and desire to secure by Letters Patent, is—

A hair-pin constructed of a single piece of 65 metal provided at one end with a hair-confining loop, the legs of the pin being provided intermediate of their ends with inward-extending bends or offsets constituting combined stops and hair-clamps, and the legs adjacent to the said loop being bent to form 70 stops or abutments to limit the inward insertion of the pin, substantially as and for the purpose specified.

In testimony that I claim the foregoing as 75 my own I have hereto affixed my signature in the presence of two witnesses.

JOHN LEICK.
